(57) **CLAIM**

The ornamental design for a lid dispenser, as shown and described.

DESCRIPTION

FIG. 1 is a top plan view of a first embodiment of my new design for a lid dispenser;

FIG. 2 is an additional top plan view thereof;

FIG. 3 is a side view of the lid dispenser shown in FIG. 1;

FIG. 4 is a cross-sectional view of the lid dispenser along line FIG. 4-FIG. 4 shown in FIG. 2;

FIG. 5 shows a perspective view thereof;

FIG. 6 is a top plan view of a second embodiment of my new design for a lid dispenser;

FIG. 7 is an additional top plan view thereof;

FIG. 8 is a side view of the lid dispenser shown in FIG. 1;

FIG. 9 is a cross-sectional view of the lid dispenser along line FIG. 9-FIG. 9 shown in FIG. 7;

FIG. 10 shows a perspective view thereof;

FIG. 11 is a top plan view of a third embodiment of my new design for a lid dispenser;

FIG. 12 is an additional top plan view thereof;

FIG. 13 is a side view of the lid dispenser shown in FIG. 1;

FIG. 14 is a cross-sectional view of the lid dispenser along line FIG. 14-FIG. 14 shown in FIG. 12;

FIG. 15 shows a perspective view thereof;

FIG. 16 is a top plan view of a fourth embodiment of my new design for a lid dispenser;

FIG. 17 is an additional top plan view thereof;

FIG. 18 is a side view of the lid dispenser shown in FIG. 1;

FIG. 19 is a cross-sectional view of the lid dispenser along line FIG. 19-FIG. 19 shown in FIG. 17; and,

FIG. 20 shows a perspective view thereof.

The broken lines shown in the drawings are intended to represent portions of the article in which the claimed design is embodied, but which form no part of the claimed design. Where a broken-line abuts surfaces provided with surface shading, that broken line is understood to represent an unclaimed boundary between claimed and unclaimed surfaces.
